(57) **CLAIM**

The ornamental design for eyeglass front, as shown and described.

DESCRIPTION

FIG. 1 is a front perspective view of the eyeglass front of the present invention;

FIG. 2 is a front elevational view of the eyeglasses of FIG. 1;

FIG. 3 is a rear elevational view of the eyeglasses of FIG. 1; FIG. 4 is a right side elevational view of the eyeglasses of FIG. 1, the left side elevational view being a mirror image thereof;

FIG. 5 is a bottom plan view of the eyeglasses of FIG. 1; and,

FIG. 6 is a top plan view of the eyeglasses of FIG. 1. The broken line showing of the earstems in FIG. 1 is for illustrative purposes only and forms no part of the claimed design.
